APPARATUS FOR BLASTING COAL

Eric Geertz, Aurora, Ill., assignor to Cardox Corporation, a corporation of Illinois

Application December 27, 1937, Serial No. 181,886

4 Claims. (Cl. 102—6)

This invention relates to new and useful improvements in apparatus for blasting coal by means of carbon dioxide.

The primary object of this invention is to provide improved apparatus for employing carbon dioxide as a blasting medium to break down materials, such as coal, and wherein such improvements as increasing the quantity and improving the quality of the yield, lessening the amount 10 of coal dust produced, and the like, are provided.

Other objects and advantages of the invention will be apparent during the course of the following description.

In the accompanying drawing forming a part 15 of this specification and in which like numerals are employed to designate like parts throughout the same,

The figure is a central longitudinal sectional view of the form of cartridge embodying this 20 invention.

For the past several years, carbon dioxide has been employed commercially as a blasting medium. Briefly, in this use of carbon dioxide, it is confined in its liquid phase in an indestructible 25 cartridge or container which, at the time of use, is placed in a suitable blast or drill hole formed in the material to be broken down. The mechanism of this type of blasting cartridge includes a suitable chemical heater unit which is positioned within the carbon dioxide receiving chamber of the cartridge. A suitable match-head is imbedded in the chemical heater composition and is energized at the time of use of the heater unit by connecting the match-head to a suitable 30 source of electricity, such as a conventional blasting magneto. When the blasting charge is to be released into the material to be broken down, the chemical heater unit is ignited and the burning of the same generates an intense heat sufficient to quickly convert the carbon dioxide to its gaseous state. Each of the cartridges used in this type of blasting is provided with a rupturable 35 wall section which is of proper construction to have a portion of the same sheared from the remainder at the pressure desired for the particular 40 blasting operation to be performed.

Due to the great many different types and characters of coal encountered involving such characteristics as cleavage or natural parting planes both as to their occurrence and direction, friability, tenacity, elasticity, hardness, compressive strength and weight of over-burden, and due to the height or thickness of the vein, which determines whether hand or power drilling can be 50 employed, it has been necessary to use cartridges 55

of different diameters and lengths. These different sized cartridges, naturally, possess different volumetric capacities insofar as the amount of carbon dioxide employed in the same is concerned.

Up to the time of development of the present 5 invention, it has been considered that the energy provided by a particular cartridge was measured theoretically by multiplying the release pressure of the charge by the volume of the charge. It has been the practice, therefore, to increase the 10 release pressure for the smaller sized cartridges. For example, the largest cartridge employed, the use of which was made possible by the height or depth of the coal vein which permitted power 15 drilling, had a maximum capacity of 100 cubic inches. Such a cartridge was customarily charged with 3 pounds of liquid carbon dioxide. The average pressure at which this cartridge charge was released was between 26,000 and 30,000 pounds per square inch. Where the coal veins 20 were too thin to employ power drilling and hand drilling had to be resorted to, the smaller cartridges, having capacities ranging from 20 to 44 cubic inches were used. These smaller cartridges, following the above referred to theory that the 25 product of the release pressure times the volume constituted the measure of energy provided by a cartridge charge, were discharged at an average release pressure of approximately 40,000 pounds per square inch.

Attempts were made from time to time to increase the quantity of coal broken down with a single charge of carbon dioxide. It was found that for a given quantity of carbon dioxide, the quantity of coal broken down could be increased 30 by raising the pressure at which the charge was released. Raising the release pressure, however, increased the shattering effect of the charge; i. e., the coal was broken down with a larger percentage of fines and the lumps which were 35 produced were less firm and therefore more easily broken during handling. This increased shattering effect was satisfactory under certain conditions, but it could not be tolerated generally in the use of carbon dioxide as a blasting medium. 40 This was due to the fact that the use of carbon dioxide costs more per ton of coal broken down than with the use of either black powder or permissible explosives. One of the outstanding advantages of the use of carbon dioxide over other 45 explosives was the ability of the same to break down the coal with a much higher yield of lump than was possible with other explosives. As lump coal is sold at a premium over fines, the final 50 profits obtained by the use of carbon dioxide as 55

a blasting medium compared favorably with other types of explosives. It was obvious, however, that increasing the quantity of yield at the expense of quality could not be favorably considered.

Attempts also were made to increase the productiveness of a charge by increasing the quantity or volume of carbon dioxide in each cartridge. It was determined that this modification did not result in any appreciable increase in the amount of coal broken down. Apparently, therefore, it was impossible to improve the quantity of coal broken down by a single cartridge charge over that which was being obtained. It was finally decided that attempts should be made to improve the quality of yield without loss of quantity. Proceeding on the theory that reducing the release pressure of a charge would result in improving the quality of yield and increasing the volume of the charge proportionately would give an energy value which was equal to that of the cartridges then being used, experiments were conducted with larger volumes and lower pressures. A number of cartridges having a 200 cubic inch capacity were prepared and discharged at release pressures of approximately 15,000 pounds per square inch. Comparing these cartridges with the largest cartridges previously used, it will be noted that these cartridges had twice the volumetric capacity and were discharged at a release pressure approximately one-half that of the largest cartridges theretofore used. It was considered that these new cartridges would produce the same quantity of yield but would provide an improvement in the quality because the product of release pressure times volume was the same for this new cartridge and the largest cartridge previously used.

Tests with these new 200 cubic inch cartridges not only demonstrated that the quality of the yield could be materially improved in this way, but that other improvements also resulted, the most surprising and unexpected of which was a very material increase in the number of tons of coal broken down per shot. In other words, a way of improving the productiveness of a cartridge had been unexpectedly discovered while attempting to improve the quality of the yield.

Naturally, additional tests were conducted employing still lower release pressures and higher release pressures which fell between the 15,000 pounds above referred to and the extremely high pressures which had been commercially used. These additional experiments clearly indicated that it would be possible to vary the volumes and pressures used if the volume of the charge and the release pressure bore certain relationships with respect to each other. In other words, it was established that the ratio of the volume to the release pressure could be varied if this ratio were maintained within a certain critical range. It was also determined that there were certain critical limits which existed with reference to minimum and maximum pressures and volumes.

With reference to acceptable release pressures, it was determined that the release pressure could not fall below the fracturing strength of the coal to be broken down; i. e., the pressure at which the coal actually could be fractured or broken loose from the face of the seam. Although the characteristics of the coal varied considerably, as noted above, it was determined that most bituminous coals could be fractured or broken loose with pressures ranging from 5,000 to 10,000 pounds per square inch. The results obtained with these pressures naturally varied in different

seams. It was determined that to properly condition the coal for mechanical loading, with the entire fall of coal loose and requiring no digging, pressures ranging from 75 per cent to 125 per cent in excess of the actual fracturing strength of the coal would produce the desired mechanical loading condition. The full range of pressures found to be most practical commercially was from 8,000 to 19,000 pounds per square inch.

By maintaining the volume of the charge within a certain range of ratios relative to the release pressure, it was found that cartridges having capacities from 50 to 200 cubic inches, which were capable of receiving charges of liquid carbon dioxide weighing from 1 pound 9 ounces to 6 pounds, more or less depending upon temperature conditions, could be used and obtain all of these improved results. Attempts to increase the volume of the charge above 200 cubic inches, or approximately 6 pounds of carbon dioxide, at release pressures ranging from 8,000 to 19,000 pounds per square inch failed to show any appreciable improvement either in the quantity or the quality of the yield. The maximum effective volume, therefore, appeared to be 200 cubic inches when using this low range of release pressures.

As stated above, the experiments conducted with this new low pressure type of cartridge clearly showed that the ratio of the volume of the charge to the release pressure must be maintained within a certain range of values to obtain the desired results. For the purpose of evaluating the volume-pressure ratio of cartridge charges, the following formula has been found to provide accurate figures:

FORMULA No. 1

$$\frac{\#CO_2 \times 14,400}{P} = \text{volume-pressure ratio}$$

#CO₂=pounds of carbon dioxide in charge.
14,400=number of cubic inches of space occupied by one pound of CO₂ gas at normal atmospheric temperature and pressure.

P=pressure at which CO₂ charge is released measured in pounds per square inch.

(One pound of liquid carbon dioxide occupies 33 1/3 cubic inches of space under the conditions and practices prevailing in the commercial use of carbon dioxide as a blasting medium. A charge of carbon dioxide weighs the same whether in a liquid or a gaseous state).

Example

$$\frac{6 \text{ lbs. } CO_2 \times 14,400}{15,500} = 5.76 \text{ volume-pressure ratio}$$

The volume-pressure ratio values for all of the cartridge charges which have been found to provide the improved and unexpected results of this invention range from 1.7 to 10.8. In applying this Formula No. 1 to the various high release pressure cartridges which have been standardized in commercial use, it was determined that their values all fell below 1.7 and extended as low as .20. This difference in the volume-pressure ratios of the two types of cartridge charges; i. e., the former high pressure charges and the new low pressure charges, is believed to be a clear indication of the improvements effected by the new low pressure type of cartridge.

As has been stated above, the only way it was found to be possible to improve the quantity of the yield, when operating in the high release pressure range was by further increasing the release pressure. Increasing the volume of the charge produced no appreciable change. It is believed

that this failure to improve the quantity of the yield by increasing the volume of the charge was due to the fact that at such high release pressure, the coal surrounding the drill or blast holes failed so quickly that the added volume of carbon dioxide had no opportunity to perform any useful work. Just the reverse is found to be true with pressures falling within the new low pressure range. It has been determined that variations in the volume of the charge more effectively produce variations in the quantity of the yield than do variations in the release pressures. In an effort to effect further improvements in the productivity of a cartridge charge of the new low pressure, large volume type, tests were conducted to determine what effect the rate or speed of discharge of the blasting charge had on the work performed. It was ascertained that the speed of release of the charge is a factor which also governs the quantity and the quality of the work performed; that the effectiveness of variations in the speed of release to govern the work performed is dependent on the relationship or ratio of the speed of release to the release pressure and the volume of the charge; that the greater the speed of release of a low pressure, large volume charge, the greater its effectiveness to improve the quantity and the quality of the yield, and that the rate or speed of release of a charge can be varied more effectively by varying the area of the discharge passage or outlet opening than by varying the release pressure.

As a result of these further tests, it was definitely established that the true measure of the available energy or available work performing energy of a carbon dioxide cartridge is not the product of the charge volume times the release pressure, but is truly expressed by the following formula:

40 FORMULA No. 2

$$\frac{\#CO_2 \div t \text{ sec.} \times 1000}{P} = \text{available energy}$$

45 $\#CO_2$ = pound of carbon dioxide in charge.
 t sec. = time in seconds required to exhaust the charge.

50 1000 = an arbitrary figure employed to enable the available energy to be expressed in terms of numerical unity.

P = pressure at which CO_2 charge is released measured in pounds per square inch.

(The time in seconds required to exhaust CO_2 through a circular orifice from high pressure to atmospheric pressure may be calculated by the formula given by Schüle in his book, Technische Thermodynamik von Prof. Dipl. Ing. W. Schüle, Berlin, Julius Springer, 1923, vol. 2.)

Example

60
$$\frac{6 \text{ lbs. } CO_2 \div .0495 \times 1000}{15,000} = 8.1 \text{ available energy}$$

The various cartridges which have been adopted commercially in this new volume-pressure carbon dioxide blasting are provided with discharge orifices having areas ranging from .89 to 2.4 square inches. The t sec. rating for these various cartridges, calculated by Schüle's formula, range from .0475 second to .0760 second. The 65 available energy ratings for these new cartridges, calculated by the above noted Formula No. 2 range from 2.0 to 10.0. The available energy ratings for all of the old high pressure, low volume cartridges, when calculated by Formula 70 No. 2 are found to fall well below 2.0.

Naturally, the chemical heater unit employed to generate sufficient heat to effect gasification of the liquid carbon dioxide charge has been a cost item for this type of blasting. It has been determined that no greater quantity of heater compound need be employed with these new low pressure, large volume charges notwithstanding the fact that approximately twice the volume of carbon dioxide is used in each one of the new cartridges as compared with the old high pressure cartridges which have been displaced by the same. This is due to the fact that the final release pressure as well as the volume of the charge governs the amount of heater compound required to condition the charge for the desired blasting operation. For example, it requires substantially the same quantity of heater compound to raise 6 pounds of carbon dioxide to 15,000 pounds per square inch as it requires to raise 3 pounds of carbon dioxide to 30,000 pounds per square inch pressure.

The problem of forming blast or drill holes to accommodate carbon dioxide cartridges has always been a controlling factor in determining the size of cartridge which can be used in a given coal vein. Where the coal predominates in the form of thin veins, hand drilling is necessary and the drill holes must be of comparatively small diameter. In high coal veins, power drilling is possible and larger drill hole diameters 30 may be employed. After determining the advantages to be obtained by the use of this new low pressure, large volume type of charge, it became necessary to devise ways and means of modifying the cartridges then used without encountering undue drilling penalties. The cartridge structure finally developed is illustrated in the drawing and will be described by reference to the same.

In the accompanying drawing, the reference character 10 designates the main body of the cartridge. This body is provided with a chamber 11 for receiving the charge of liquid carbon dioxide and the chemical heater unit 12. The rear or charging end of the cartridge has a charging 45 cap or plug 13 threaded therein. A shoulder 14 is provided within the bored out end of the cartridge body to receive a gasket 15 which is compressed by the charging plug 13 when the latter is fully threaded into the body of the cartridge. 50 This shoulder 14 also acts as a seat for the head 16 of the chemical heater unit 12.

This chemical heater unit employs a match-head 17 which includes the circuit wires 18 and 19. The wire or terminal 18 is arranged to have 55 electric contact with the electrode 20 which is suitably mounted within the charging plug or cap 13 and is properly insulated therefrom. The remaining lead wire 19 of the match-head is grounded to the cartridge body. This ground also includes the charging plug or cap 13. A suitably insulated socket 21 is formed transversely in the charging plug or cap 13 for receiving one lead or wire from a blasting magneto. This socket 21 permits the electrode 20 to make 60 contact with the magneto wire detachably inserted in the said socket. A second socket 22 is formed in the charging plug 13 for the reception of the second lead wire from the magneto. This second lead wire is properly grounded or has 65 electrical connection with the plug 13 for completing the circuit through the match-head 17.

Charging of the liquid carbon dioxide into the chamber 11 of the cartridge body is effected by means of a suitable charging plant which is 70 75

provided with a charging clamp or head that properly engages the plug 13. The adjustable valve 23 can be manipulated while the charging clamp or head is associated with the charging plug of the cartridge for making and breaking communication between the charging plant and the chamber 11 of the cartridge body.

The discharge end of the cartridge body is formed with a shoulder 24 against which seats 10 a packing gasket 25 and a disc 26 which is adapted to have the central portion of the same sheared from the marginal portion by the blasting pressure developed within the chamber 11 of the cartridge. This central portion of the disc 15 is sheared by the edge 27 of the discharge cap shank 28. The discharge cap is designated by the reference character 29.

The shearing or rupturing of the disc effects communication between the chamber 11 of the 20 cartridge and the interior of the cap 29. To permit very rapid discharge of the blasting charge from the cap 29, a series of angle ports 30 are provided in the cap. For the larger cartridges, twelve of these angular discharge ports 30 are 25 provided. The smaller cartridges can be rapidly discharged with a smaller number of ports. It will be noted that these discharge ports are arranged at a proper angle to effect release of the blasting charge in a rearward direction. This 30 controlled directional release of the blasting charge very effectively functions to retain the cartridge within a drill hole and to prevent the development of pressure between the inner end of the cartridge and the inner end of the drill 35 hole which is a very desirable feature. It has been determined that releasing a large volume of carbon dioxide gas from the discharge cap through a smaller number of angular discharge ports which are of greater diameter than those 40 illustrated fails to effect the desired directional discharge of the charge. A fewer number of larger discharge ports, therefore, will not produce the desired effect of aiding in retaining the blasting cartridge within the drill hole although 45 the desired rapid rate of release of the charge is effected. It has been determined that the discharge ports formed in the cap 29 should be arranged at an angle of approximately 45 degrees and should each have a diameter of approxi- 50 mately $\frac{3}{8}$ of an inch. In providing this large number of ports in a single cap, it has been found desirable to arrange the same in two series of six ports to a series with the ports of one series staggered with respect to the ports of the second 55 series.

The cartridges normally used, i. e., the low volume high pressure cartridges, were provided with outside diameters of $1\frac{3}{4}$ inches and $2\frac{1}{2}$ inches. The overall length for the cartridge 60 bodies of the $1\frac{3}{4}$ inch cartridges varied from $20\frac{1}{2}$ inches to $43\frac{3}{8}$ inches. The thickness of the side chamber wall for each of these cartridges was .25 inch. These cartridges had volumetric capacities ranging from 20 to 44 cubic inches. 65 The overall length of the $2\frac{1}{2}$ inch cartridges was $42\frac{3}{8}$ inches. The thickness of the chamber wall for this type of cartridge was $\frac{1}{2}$ of an inch. This type of cartridge had a volumetric capacity of 100 cubic inches.

70 To provide the increased capacity for the low pressure cartridges, the old $1\frac{3}{4}$ inch outside diameter cartridge was increased to 2 inches outside diameter. The length of the different 2 inch cartridges ranged from $30\frac{1}{4}$ inches to 75 $54\frac{1}{4}$ inches. The chamber wall thickness for

this type of cartridge was reduced to .18 $\times$. This reduction in wall thickness was made possible by the reduction in release pressure employed with this type of cartridge. This 2 inch cartridge, due to varying lengths, is provided with volumetric capacities of 50, 80 and 100 cubic inches. 5

The old $2\frac{1}{2}$ inch outside diameter cartridge was increased to 3 inches. The chamber wall thickness was reduced to .25 inch, which reduction was made possible by the reduction in release pressure. The overall length of the body portion of this 3 inch cartridge was standardized at $46\frac{1}{8}$ inches. This cartridge had a volumetric capacity of 200 cubic inches. 10

To effect as rapid discharge of the blasting medium as was possible, the inner wall surface of the cartridge chamber 11 was made streamlined, as indicated at 31. The diameters of the outlet openings were increased as much as possible. The diameter of the outlet opening, of course, is controlled by the outside diameter of the cartridge. The old $1\frac{3}{4}$ inch outside diameter cartridge had an outlet opening which was $\frac{3}{4}$ of an inch in diameter. The new 2 inch outside diameter cartridge was provided with an outlet 25 opening which measures $1\frac{1}{8}$ inches in diameter. The old $2\frac{1}{2}$ inch outside diameter cartridge was provided with an outlet opening having a diameter of $1\frac{1}{4}$ inches. The new 3 inch cartridge was provided with an outlet opening having a diameter of $1\frac{3}{4}$ inches. These increases in outlet 30 opening diameters and the streamlining of the discharge end of the cartridge chamber resulted in a much more rapid rate of discharge of the blasting medium. 35

As has been generally stated above, the use of the low pressure large volume cartridge resulted in numerous improvements over the results obtained with the former high pressure cartridges. The shattering effect of the low pressure charge 40 was much less than with the high pressure charge. The yield possessed a higher percentage of lump coal over fine and the lumps produced were fully twice the size of the lumps formerly produced. The larger lumps also were firmer and resulted in much less breakage during handling. Due to the production of a larger quantity of lump 45 and larger lump sizes, the coal dust produced by a blast was materially reduced. It was determined by visibility tests employing light sources and an exposure meter, that 3 minutes after the 50 firing of a low pressure charge, visibility was within 14 percent of being normal and 10 minutes after firing visibility had returned to normal. With high pressure charges visibility was 55 per cent below normal after 3 minutes had elapsed. 55

An increase in tonnage of coal per shot was effected which was very material. For example, the high pressure 100 cubic inch cartridge, released at an average of 30,000 pounds per square inch, broke down on an average of 5 tons of coal. The new 200 cubic inch cartridge released at a pressure of 15,000 pounds per square inch broke down on an average of 8 tons per shot. This 60 increased yield per shot naturally enables a working face to be brought down with fewer shots which reduces the cost by effecting a saving on drilling time. The cost of breaking down a ton of coal by the low pressure cartridge was 65 found to be 20 per cent less than the cost with high pressure cartridges. 70

It also was determined that the large volume and low pressure of the new type of cartridge rolls the coal out from the face in a substantially 75

better condition for easy and consequently lower cost mechanical loading. It also has an effective spread to a much greater area resulting in breaking down more coal per shot, shearing straighter ribs, roof and face resulting in substantially eliminating overhanging coal on the ribs and face. Overhanging coal has always presented a real hazard to miners in cleaning out coal deposited close to the base of the ribs and face. The 5 vision of straighter ribs, roof and face also slightly increases the tonnage produced from a room of a given size.

It is to be understood that the forms of this invention hereinafter shown and described are to be taken as preferred examples of the same, and that various changes in the shape, size and arrangement of parts may be resorted to without departing from the spirit of the invention or the scope of the subjoined claims.

Having thus described the invention, I claim:

1. In apparatus employed for breaking down coal in a mine by suddenly releasing into the coal a highly compressed gaseous charge of carbon dioxide which has been confined as a liquid and converted to its gaseous state by the application of intense heat at the time of effecting release of the charge, the improvement which comprises a cartridge having a charge receiving chamber possessing a volumetric capacity of 50 to 200 cubic inches and a discharge orifice having a diameter of from $1\frac{1}{8}$ inches to $1\frac{3}{4}$ inches, means in said chamber for heating the carbon dioxide charge to effect gasification of the same, and a wall section closing said discharge orifice and being of a character to rupture at the development of a pressure within the chamber falling between 8,000 and 19,000 pounds per square inch.

2. In apparatus employed for breaking down coal in a mine by suddenly releasing into the coal a highly compressed gaseous charge of carbon dioxide which has been confined as a liquid and converted to its gaseous state by the application of intense heat at the time of effecting release of the charge, the improvement which comprises a cartridge having a charge receiving chamber capable of confining a liquid charge of from 1 pound, 9 ounces to 6 pounds of carbon dioxide and a discharge orifice having a diameter of from $1\frac{1}{8}$ inches to $1\frac{3}{4}$ inches, means operatively associated with the cartridge for gasifying the charge, and means for controlling said discharge orifice to effect discharge of the gasified charge at a pressure falling between 8,000 and 19,000 pounds per square inch, the particular liquid charge, orifice diameter, and discharge pressure combination of the cartridge being such as to provide an available work performing energy value of from 2.0 to 10.0 when calculated by Formula No. 2 appearing in the accompanying specification.

fying the charge, and means for controlling said discharge orifice to effect discharge of the gasified charge at a pressure falling between 8,000 and 19,000 pounds per square inch.

3. In apparatus employed for breaking down coal in a mine by suddenly releasing into the coal a highly compressed gaseous charge of carbon dioxide which has been confined as a liquid and converted to its gaseous state at the time of effecting release of the charge, the improvement which comprises a cartridge having a charge receiving chamber capable of confining a liquid charge from 1 pound 9 ounces to 6 pounds of carbon dioxide and a discharge orifice having a diameter of from $1\frac{1}{8}$ to $1\frac{3}{4}$ inches, means for heating the liquid carbon dioxide charge to effect gasification of the same, and a wall section closing said discharge orifice and being of a character to rupture at the development of a pressure within the chamber falling between 8,000 and 19,000 pounds per square inch, the particular liquid charge, discharge orifice diameter, and discharge pressure combination of the cartridge being such as to provide an available work performing energy value of from 2.0 to 10.0 when calculated by Formula No. 2 appearing in the accompanying specification.

4. In apparatus employed for breaking down coal in a mine by suddenly releasing into the coal a highly compressed gaseous charge of carbon dioxide which has been confined as a liquid and converted to its gaseous state at the time of effecting release of the charge, the improvement which comprises a cartridge having a charge receiving chamber capable of confining a liquid charge of from 1 pound 9 ounces to 6 pounds of carbon dioxide and a discharge orifice having a diameter of from $1\frac{1}{8}$ inches to $1\frac{3}{4}$ inches, means operatively associated with the cartridge for gasifying the charge, and means for controlling said discharge orifice to effect discharge of the gasified charge at a pressure falling between 8,000 and 19,000 pounds per square inch, the particular liquid charge, orifice diameter, and discharge pressure combination of the cartridge being such as to provide an available work performing energy value of from 2.0 to 10.0 when calculated by Formula No. 2 appearing in the accompanying specification.

ERIC GEERTZ.
